UNITED STATES PATENT OFFICE.

HARRY R. HAYSLEY, OF SOUTH LOUISVILLE, KENTUCKY.

RULE-HOLDER.

1,250,166.

Specification of Letters Patent. Patented Dec. 18, 1917.

Application filed November 12, 1913. Serial No. 800,640.

To all whom it may concern:

Be it known that I, HARRY R. HAYSLEY, a citizen of the United States, residing at South Louisville, in the county of Jefferson, State of Kentucky, have invented certain new and useful Improvements in Rule-Holders; and I do hereby declare the following to be a full, clear, and exact description of the invention, such as will enable others skilled in the art to which it appertains to make and use the same.

The present invention is directed to improvements in rule holders, and has for its object to so construct a device of this character that the same can be easily and quickly secured in the pocket of a garment, and is so constructed that a rule engaged therein will be frictionally retained in place so that should the person wearing the device lean over the rule will be prevented from becoming accidentally disengaged.

With this and other objects in view, this invention resides in the novel features of construction, formation, combination and arrangement of parts to be hereinafter more fully described, claimed and illustrated in the accompanying drawing, in which:—

Figure 1 is a side elevation of the device.

Fig. 2 is a rear view.

Fig. 3 is a sectional view on lines 3—3 of Fig. 2.

The holder comprises a casing 1, which is formed from sheet metal and consists of inner and outer walls 2 and 3, respectively, and side walls 4, said casing being rectangular in cross section so as to conform to the shape of the rule when folded.

The inner wall 3 terminates at its upper edge in a downwardly extending tongue 5, the same being curved inwardly, so as to provide the flared lower end 7 which permits

the upper edge of the pocket to be readily engaged between the inner wall and tongue.

The tongue 5 and inner wall 3 are provided with spurs 8, which coact to grip the material forming the pocket of a garment so as to firmly hold the casing in the pocket.

The sides 4 are each provided with cuts 9; the materials defined by said cuts are forced inwardly to produce resilient fingers 10 which are adapted to yieldingly engage the side edges of a folded rule when the same is engaged in the casing and pocket of the garment bearing the device, thus preventing accidental disengagement of the rule 55 should the wearer of the device lean over.

What is claimed is:—

A rule holder constructed and arranged to hold a rule resiliently centered between its sides and comprising a single tubular member rectangular in cross section and provided on opposite sides with downwardly extending spring tongues intermediate its ends and adapted to grasp the sides of a rule between their lower parts, and an extension from the upper end of the back of said tubular member bent downward to form a spring tongue and curved away from the back at its lower end, said tongue and back having upwardly extending prongs struck from the tongue 70 and member, the prongs on the lower part of the member being spaced away from the center to permit uninterrupted access of the user's finger to the tongue whereby the tongue may be sprung away from the back. 75

In testimony whereof, I affix my signature, in the presence of two witnesses.

HARRY R. HAYSLEY.
